CLAIM

The ornamental design for a storage and display carton, as shown and described.

DESCRIPTION

FIG. 1 is a perspective view of the storage and display carton, embodying our new design;

FIG. 2 is an elevational front view thereof;

FIG. 3 is an elevational back view thereof;

FIG. 4 is a left side elevational view thereof;

FIG. 5 is a right side elevational view thereof;

FIG. 6 is a top plan view thereof; and,

FIG. 7 is a perspective view thereof, with the tearing portion removed.

The broken line showing of a storage and display carton is for illustrative purposes only and forms no part of the claimed design.
